DESIGN FOR A TRAILER

Thurlow E. McFall, Sparta, Mich.

Application May 20, 1935, Serial No. 56,918

Term of patent 14 years

To all whom it may concern:

Be it known that I, Thurlow E. McFall, a citizen of the United States, residing at Sparta, in the county of Kent and State of Michigan, have invented a new, original, and ornamental Design for a Trailer, of which the following is a specification, reference being had to the accompanying drawing, forming part thereof.

In the drawing:

Fig. 1 is a side elevation of a trailer in accordance with my new design.

Fig. 2 is a plan view thereof.

Fig. 3 is a front end elevation, and

Fig. 4 is a rear elevation.

I claim:

The ornamental design for a trailer, substantially as shown.

THURLOW E. MCFALL.
